[57] CLAIM

The ornamental design for a corner connector for use in the construction of a drawer, as shown and described.

DESCRIPTION

FIG. 1 is a perspective view of a corner connector for use in the construction of a drawer, showing my new design;

FIG. 2 is a left side elevational view thereof;

FIG. 3 is a rear elevational view thereof;

FIG. 4 is a top plan view thereof;

FIG. 5 is a right side elevational view thereof;

FIG. 6 is a front elevational view thereof;

FIG. 7 is a bottom plan view thereof;

FIG. 8 is a perspective view of a corner connector for use in the construction of a drawer, showing an alternate embodiment of my new design;

FIG. 9 is a left side elevational view thereof;

FIG. 10 is a rear elevational view thereof;

FIG. 11 is a top plan view thereof;

FIG. 12 is a right side elevational view thereof;

FIG. 13 is a front elevational view thereof;

FIG. 14 is a bottom plan view thereof; and,

FIG. 15 is a perspective view of the corner connector of FIG. 1, showing the side not shown in FIG. 1.
